CLAIM

The ornamental design for a display screen with animated graphical user interface, as shown and described.

DESCRIPTION

FIG. 1 is a front view of a first image of a first embodiment of a display screen with animated graphical user interface showing our new design;

FIG. 2 is a front view of a second image thereof;

FIG. 3 is a front view of a third image thereof; and,

FIG. 4 is a front view of an alternate third image thereof. The appearance of the image sequentially transitions between the images shown in FIGS. 1-3. Alternatively, the appearance of the image sequentially transitions between the images shown in FIGS. 1, 2, and 4. The process or period in which one image transitions to another image forms no part of the claimed design.

The broken lines of uneven length show a screen for displaying the animated graphical user interface and form no part of the claimed design. The broken lines of short even length shown in the drawing illustrate portions of the display screen with animated graphical user interface that form no part of the claimed design. The vertical broken line of longer even length shown in FIG. 3 forms part of the claimed design.
